SAMUEL LIPPINCOTT GRISWOLD KNOX, OF NEW YORK, N. Y.

APPARATUS FOR SIGHTING GUNS.

Application filed December 27, 1922. Serial No. 609,359.

My invention relates to apparatus for sighting guns and has particular reference to methods and apparatus for correcting errors in sighting naval guns caused by the 5 tilting of the axis of the trunnions out of a horizontal plane by the rolling and pitching of the ship.

When a naval gun, as ordinarily mounted and sighted, is fired at an angle of elevation other than zero, it is necessary that the axis of the trunnions of the guns be horizontal in order that the plane of the trajectory of the gun shall be that indicated by the gun sights. Errors in sighting are introduced whenever the trunnions are not 15 horizontal and the gun is elevated. These errors are so slight at low angles of elevation and for the angles of trunnion tilt likely to occur when firing off the broadside 20 that, though well known theoretically and treated mathematically in text-books, they have not, until a relatively recent date, been considered to have any importance in practice. The necessity in war of sometimes 25 firing at long ranges ahead and astern has now given the question a practical importance not previously realized.

When a naval gun is pointed approximately ahead or astern the axis of its trunnions points athwartship, and is therefore tilted by the roll of the ship, which is generally much greater than the pitch, which causes the tilting of the trunnions when the gun is pointed abeam. As there is no difference in principle, but merely in degree, 35 between the effects of roll, pitch, or a combination of both, all of these conditions will be hereinafter referred to as roll.

The theory of the sighting of naval guns 40 has heretofore been based on the assumption that the axis of the bore of the gun always lies in a vertical plane having a fixed relation to another vertical plane passing through the line of sight. This is true, 45 however, only if the trunnions of the gun do not tilt, and the trunnions do tilt whenever the ship rolls. The effect of this combined tilting and elevation can, under modern conditions of warfare, become so great as to 50 cause an error in deflection, azimuth, of a mile or more, in the case of a large gun fired at long range in a rough sea, and trained

within approximately 30° of the longitudinal axis of the ship. Since this error changes from extreme right to extreme left 55 within a few seconds as the ship rolls from side to side it cannot be corrected by "spotting", as the trial and error system applied to the correction of other errors of gun fire is called.

When the bore of the gun is elevated with reference to the line of sight, and the trunnions are tilted, the roll of the ship causes the axis of the bore to generate a segment of the surface of a cone having as its axis 60 a horizontal line corresponding to the axis of the bore of the gun when in the horizontal position, that is, at 0° elevation. This introduces two errors into the sighting of the gun not heretofore compensated for; one the 65 error in azimuth or deflection before referred to and the other an error in elevation of the gun.

Referring first to the error in azimuth; as 70 naval guns sights are ordinarily arranged, the telescope points along a line approximately parallel to the axis of the gun, and this line of sight is not varied if and as the bore of the gun moves back and forth on the surface of the cone due to the combined 75 effect of trunnion tilting and elevation. The line of sight is supposed to indicate the plane of the trajectory, so that, if the line of sight terminates in a target it is assumed that the projectile will hit the target or at 80 least fall along the line of sight, whatever the elevation of the gun. The plane of the trajectory, however, swings back and forth through an angle equal to the projection on a horizontal plane of the conical segment 85 generated by the axis of the bore of the gun as the trunnions are tilted. But the line of sight does not change. It therefore lies in the plane of the trajectory only when the trunnions are horizontal, although the assumption has been that it lies in the plane 90 of the trajectory under all conditions.

The second error caused by the tilting of the trunnions, the error in the elevation of the gun, is not ordinarily corrected at present because the angle of elevation at which to set the gun, is calculated for that position of the gun at the very peak of its path in generating the segment of the surface of the 100

cone. But the angle of elevation does not remain at this value. It grows less as the gun swings by the peak position to either left or right, the error being greatest when

5 the gun is at the ends of its swing.

By my present invention I correct both of these errors first by continuously adjusting the line of sight to lie in a plane parallel to the plane of the trajectory, and then by 10 adjusting the line of sight in the first mentioned plane by a proper amount to compensate for the "dipping," or reduction of elevation, of the gun as it swings by the peak or point of maximum elevation as the trunnions are tilted.

15 My invention provides means for indicating at all times the angle by which the line of sight must be swung to the left or right, as the trunnions tilt more or less, in order that it may always lie in a plane parallel to the plane of the trajectory, or, alternately, my invention provides means for indicating at all times the amount of the error in azimuth, without shifting the line of sight, in 20 order that the gun or guns may not be fired when the error caused by the tilt of the trunnions is more than a predetermined amount. Means are therefore provided for indicating at all times the departure of the 25 axis of the trunnions from the horizontal, and the consequent tilting of the plane of the trajectory. One way of doing this is to sight to the horizon on a line parallel to the axis of the trunnions; another way is to 30 employ a gyroscope; and another is to establish the reference plane by the use of a pendulum of the dead-beat type. Means for 35 adjusting the line of sight angularly with respect to the axis of the bore of the gun 40 allow the line of sight to be moved both into the reference plane, to cause it to lie parallel to the plane of the trajectory, and through a vertical angle sufficient to compensate for the reduction in the angle of elevation of the 45 gun caused by the tilting of the trunnions.

50 It is not necessary that the reference plane should be established with absolute accuracy. Even at high angles of elevation the error in azimuth caused by a trunnion tilt of less than 1° is practically negligible, so that an apparatus which corrects, or indicates an error equivalent to less than 1° tilt of the trunnions is sufficiently accurate. There is 55 no difficulty in establishing the reference plane with much less than 1° of error by any of the means just mentioned.

60 My present invention further comprises the novel structure, combination of parts and features described below, for a clear understanding of which, reference will be made to the accompanying drawings in which:

65 Fig. 1 is a view in side elevation of a naval gun provided with the apparatus of my invention.

Fig. 2 is a plan view of this gun.

Fig. 3 is an enlarged view of the connection between the outer end of the sight rod and the sight yoke.

Fig. 4 is an end view of the pendulum indicator and reference point in operative relation.

Fig. 5 is view of a modified form of pendulum indicator.

Figs. 6 and 7 show the pendulum indicator modified for electric fire control, and

75 Figs. 8, 9 and 10 are explanatory diagrams, Fig. 8 showing in elevation the angular relationship between the line of sight and the axis of the gun bore; Fig. 9 representing these relationships as seen in plan view; and Fig. 10 as seen in end view.

80 With reference first to Figs. 8, 9 and 10 of these drawings, the axis of the bore of a gun, which by way of example, is assumed to be trained directly ahead or astern of the ship and pointed at 0° elevation is represented by the line AB. The line of sight CD lies parallel to the axis AB. Under these conditions the tilting of the plane of the trunnions will not cause the axis AB to be taken off from the target.

85 Assuming that the plane of the trunnions TT, Figure 10, remains horizontal, if the gun is elevated through an angle " a " so that 90 the axis AB assumes a position A'B' the line of sight CD remains approximately horizontal and, if angle " a " has been correctly calculated for the range, wind resistance and other factors usually taken into 95 consideration, the projectile fired from the gun in this position should hit the target or at least fall within the plane of the line of sight.

100 Should the ship be moving in a fairly heavy sea, however, the plane of the trunnions TT will not remain horizontal, but will be continuously oscillating from port to starboard through a certain angle of roll with respect to the horizontal. Assuming 105 that the plane of the trunnions is tilted through an angle of roll " b " (Fig. 10) to a position T'T" and that the gun is elevated by an angle " a ", the axis of the bore AB will assume the position A''B'' and 110 will make an angle " c " (Fig. 9) with respect to the vertical plane through the axis AB; that is, with respect to the vertical plane through the axis of the bore with the trunnions horizontal. If the gun is 115 fired in this position the plane of the trajectory will be a substantially vertical plane through the line A''B'', and the projectile will fall wide to the right of the target, because the line of sight CD which passes through the target still remains in a horizontal plane and has not been shifted in 120 this plane to compensate for angle " c ". In order to correct for this error in azimuth, 125 which amounts to the angle " c ", I establish 130

7- a reference plane into which the line of sight CD may be adjusted to determine the value of the angle "c" through which the axis of the bore of the gun must be rotated 8 in order to train the gun back onto the target.

This reference plane may be conveniently established by means of a pendulum of the dead beat type arranged with an indicating 10 pointer mounted on an axis parallel to the axis of the gun bore. This indicator, therefore, will always remain in a vertical plane parallel to another vertical plane through the axis of the bore of the gun and hence 15 parallel to the plane of the trajectory.

This pendulum indicator will therefore establish the point D', when the trunnions are tilted to the angle "b" and the line of sight may easily be brought to lie in this 20 reference plane by adjusting it to the position CD'. This will cause the line of sight to be taken off of the target, or, in other words, the cross hairs of the sighting telescope will move away from the target. If 25 the gun is now trained to bring the cross hairs back onto the target, the axis of the bore of the gun will be rotated through the angle "c", from the position A''B'' to the position AB, and will again be trained in 30 the plane of the target.

Inasmuch as the axis of the bore of the gun sweeps the surface of a segment as a cone as above described, when the trunnions are tilted by the roll of the ship, the angle 35 of elevation "a" will be reduced in value to the angle "a'" (Fig. 8). In order to correct for this change in elevation of the gun, the line of sight CD may now be moved, in a vertical plane, through an angle 40 equal to the difference between angle "a" and angle "a'" to the position CD''. This will again cause the cross hairs of the sighting telescope to move off from the target and, in bringing them back on to the target, the angle of elevation of the gun 45 will be brought back to the correct value, angle "a".

These adjustments to correct for errors caused by trunnion tilt may be made in 50 separate steps, as they have been described above, for the sake of clearness, or they may be made simultaneously, inasmuch as there is a definite, fixed relation between the change of angle of azimuth, or horizontal angle, and the change of angle of elevation, or vertical angle.

Referring now to Figs. 1 and 2 of the accompanying drawings, the gun base 10 supports the framework 11 on the usual vertical bearing so that it may be freely moved about this bearing, thru any horizontal angle desired, by means of the training handwheel 12. The framework 11 carries trunnion 60 bearings in which the trunnions 13 on the gun mount 14 are carried and provision is

made for rotating the gun about trunnions 13, thru any vertical angle desired, by means of the pointing handwheel 15. The gun barrel 16 slides in the gun mount 14 when the gun is discharged, the recoil being taken up 70 by recoil pistons and cylinders located in the lower part of the gun mount.

The sight yoke 25 is universally mounted, over the center of the gun mount, this universal mounting including two horizontal pivots 17, secured to bosses 18, on the gun mount, and the single vertical pivot 19, on the intermediate member 20. The sight yoke 25, accordingly, may be moved in either a horizontal or a vertical plane in order to make proper adjustment both in azimuth and elevation for the factors for which such adjustments are customarily made; such as range, speed of enemy's ship, speed 80 of own ship, wind resistance, drift, etc. 85

The mechanism for controlling the movement of the sight yoke to make these adjustments comprises the "sword" 21 carried in a curved slide called the "scabbard" which is fixed to a bracket on the gun mount 14, the curvature of the slide being determined by an arc struck from the pivot 17 as a center, so that, as the sword 21 is moved in a vertical plane by means of the adjusting handwheel 22, it will move in the arc of the circle having the pivot 17 as its center. In the head 23 of the sword there is a pair of curved ways 24, cut on the segment of a circle about the pivot 19 as its center. The extension head 26 on the sight yoke 25 has 90 ways cut in the lower surface thereof to coat with ways 24 in the sword head 23; and adjusting wheel 27 which operates feed screw 28, passing through a nut 29 in the sight yoke extension, provides means for 100 moving extension head 26 in a horizontal plane along the ways 24. By means of this mechanism the sight yoke 25 may be readily adjusted in both a horizontal and a vertical plane by rotating the handwheels 22 and 27. 110 These handwheels are operated by the "sight setter".

Up to this point the entire mechanism of the construction of the gun is of the ordinary type in common use. In accordance 115 with my invention I mount the gun trainer's telescope 30, and the gun pointer's telescope 31, upon sight rods 32 and 33 which are universally mounted upon the sight yoke 25 so that the sight rods, and consequently the telescopes, may be adjusted in either a horizontal or a vertical plane with respect to the sight yoke. This universal mounting comprises intermediate members 34 and 34', having vertical bearings 35 and 35' in 120 brackets extending from the sight yoke, and provided with bifurcated heads 36 and 36' adapted to receive the small trunnions 37 and 37' on sight rods 33 and 32 respectively. A connecting rod 38 transmits the motion 130

of sight rod 33 to sight rod 32 so that the axes of these rods always remain in parallel relation to each other.

At the outer or left hand end of sight rod 33, a forked member 39 (Figs. 3, 2 and 1) partially embraces the sight rod and is pivotally connected thereto by a pair of horizontal bearings 40. The lower end of forked member 39 is secured by a ball and socket joint 41 to a fixed point on the sight yoke 25 (see Fig. 1). The outer end of sight rod 32 is connected in a similar manner to another fixed point on sight yoke 25. By means of this arrangement the simultaneous adjustment for correction for errors in azimuth and elevation is secured, since any rotation of sight rods 33 and 32 about pivots 35 and 35' respectively will cause a vertical depression of the outer end of the sight rod, depending upon the amount of horizontal movement given to the sight rod.

In order to give the proper horizontal movement to sight rod 33 to keep its axis in the reference plane established by the pendulum indicator, to be later described, a sight rod extension 42 is rigidly attached to the sight rod, as by means of the projections 43, and extends rearwardly, terminating in a lateral projection 44 on which is mounted a reference point 45, transversely adjustable on projection 44 by means of slide 59 and its cooperating screw 60 and handwheel 61, in order to correct for the angle of deflection received from the fire-control room. A scale 62 on projection 44 indicates the amount of adjustment of slide 59. The movement of the sight rod is controlled through the adjusting wheel 46, mounted near the end of extension 42 and provided with the screw 47 which coacts with a nut 48 carried on sight yoke 25. A dead beat pendulum 49 contained in an appropriate housing is so mounted that its pendulum axis 50 is located in a vertical plane parallel to the vertical plane through the axis of the gun bore, and that reference point 45 will be opposite axis 50 when the gun is pointed at 0° elevation. The pendulum will then indicate a reference plane parallel to the plane of the trajectory, under all conditions of trunnion tilt. The motion of the pendulum is transmitted to a pendulum indicator 51 which is located in proximity to the reference point 45 and which may conveniently be curved into the arc of a circle so as to remain at about the same distance from reference point 45 for all angles of elevation of the gun. With the trunnions of the gun horizontal, in which position they are represented in Fig. 2, pendulum indicator 51 will be in mid-position.

When the gun is to be fired under conditions where trunnion tilting does not have to be taken into account, as, for example, when the sea is smooth, slide 59, carrying

reference point 45, is set in the mid-position of scale 62, and the sight setter adjusts sight yoke 25 by means of hand wheels 22 and 27, for the angles of elevation and deflection (azimuth) which he receives from the fire-control room, just as he would do if the gun were not equipped with apparatus for compensating for trunnion tilt. The gun is then sighted on the target and fired. 75

When, however, the gun is to be fired while the ship is in a heavy sea, under conditions where it is desirable to compensate for trunnion tilting, the sight setter adjusts sight yoke 25 by hand wheel 22 for the angle of elevation received from the fire-control room, and he turns handwheel 27 to place sight yoke 25 in the mid-position of its azimuth scale on sword head 23. He then manipulates handwheel 61 to set reference point 45 to the right or left of the mid-position of scale 62 by the angle of azimuth received from the fire-control room. 80

The "gun trainer" looking through telescope 30 and actuating handwheel 12, and the "gun pointer" looking through telescope 31 and operating handwheel 15, keep the cross hairs of the telescopes upon the target. A fourth man now manipulates handwheel 46 so as to keep reference point 45 in alignment with the pendulum indicator 51, following this indicator as it swings back and forth upon its axis 50. The motion of indicator 51 is only apparent because, actually, it always remains in a plane parallel to the plane of the trajectory. It is the gun itself which really swings with reference to pendulum indicator 51. When the fourth man turns handwheel 46 to keep reference point 45 in alignment with the pendulum indicator, he causes the sight rod 33 to move transversely with reference to sight yoke 25, in one direction or another, so that its axis, and therefore the line of sight through the telescopes, always lies in the reference plane established by pendulum indicator 51, which is a vertical plane parallel to the vertical plane passing through the axis of the gun bore—the plane of the trajectory. 100

As sight rod 33 is moved transversely with reference to sight yoke 25 the mechanism illustrated in Fig. 3, for connecting the outer end of the sight rod to a fixed point on sight yoke 25, causes the outer end of the sight rod to be automatically depressed by a predetermined amount depending upon the amount of lateral movement of the sight rod. This depression of the end of the sight rod 33 about the horizontal axis 37 compensates for the reduction in elevation of the gun caused by the tilt of the trunnions. The movement of the line of sight with respect to sight yoke 25 caused by the operation of handwheel 46 throws the cross hairs of the telescopes off the target, and the gun trainer and gun 115 120 125 130

pointer, by operating the handwheels 12 and 15 respectively, immediately bring their cross hairs back on the target and, if the gun is now fired, the plane of the trajectory will be 5 parallel to the plane of the line of sight, and the gun will be re-elevated to the proper angle and the projectile will therefore hit the target.

In case it is thought unnecessary to compensate for the error in elevation of the gun caused by the tilting of the trunnions, the reference point 45, may be mounted directly on sight yoke 25, means, such as slide 59 and handwheel 61, being provided for its 10 adjustment. Telescopes 30 and 31 may then be mounted on the sight yoke in the ordinary manner, and the mechanism illustrated in Fig. 3 for depressing the outer end of the sight rod, as well as all of the mechanism 15 for causing motion of the telescopes relative to the sight yoke 25, may be dispensed with. This simplifies the apparatus, the movement of the line of sight to keep it in the reference plane of the pendulum indicator being 20 cured by means of the handwheel 27.

In practice it may be found too difficult, or too expensive, to constantly shift the line of sight back and forth to keep the reference point 45 in the plane of the pendulum indicator 51 and/or to shift the gun in azimuth with sufficient speed to keep the telescope on the target. For this reason I provide the alternative means for preventing errors 25 caused by trunnion tilt, which consists in indicating at all times the amount of error in azimuth existing by virtue of the tilting of the trunnions, so that the gun or guns may not be fired when this error is more than a predetermined amount. For this purpose I 30 mount on the pendulum indicator 51 a plate 52 (Fig. 5), which may conveniently be made of transparent material, and on which is drawn a diagram so constructed as to indicate the permissible limits of error at various angles of elevation of the gun.

In constructing this diagram the vertical center line 50-53 is placed in the plane of the indicator 51, and various horizontal lines 53 to 58 inclusive are drawn at such heights 35 above the pendulum axis 50 that the reference point 45 will fall on them at certain chosen angles of elevation of the gun, say, for example, at 3° , 6° , 9° , 12° and 15° respectively. Assuming that reference point 45 falls on line 54 at 3° elevation; on line 55 at 60° elevation; etc., then a distance is measured off horizontally on line 54, on each side of the center line 50-53, such that, if the reference point 45 is allowed to deviate further 40 from the center line than the amount so laid off, there will be an error in azimuth, at the range corresponding to 3° elevation equal to more than the permissible maximum error in azimuth, say for example 100 yards. A distance corresponding to this

predetermined permissible maximum error in yards is then laid off for each of the chosen angles of elevation, and through the points so found, the curves WX and YZ are traced, forming the boundaries of the transparent plate 52.

When this alternative means of eliminating the errors caused by trunnion tilt is adopted, reference point 45 is mounted in fixed position on sight yoke 25, the sights 75 are used as ordinarily mounted and with no attempt to oscillate the telescopes so as to compensate for the errors of trunnion tilt, but merely to indicate, by the movement of the reference point 45 back and forth across 80 the lines WX and YZ, the times when the error is within or without the maximum permissible limits.

By mounting a plate 63 (Figures 6 and 7) of insulating material, on the pendulum 85 indicator 51, and providing on one surface of this plate an insert 64 of electrically conducting material, the shape of the insert 64 being determined by the curves WX and YZ, and by substituting for reference point 90 45 a contact point or roller 65 resting lightly against plate 63, the gun fire may be electrically controlled.

The passing of the contact point back and forth across the space between curves WX 95 and YZ may be made to close and open the firing circuit 66, or to light a lamp, to ring a buzzer, or otherwise prevent or warn against the firing of the gun or guns, when the error due to the trunnion tilt is greater than the 100 permissible mount, as shown by the indicator 45, falling outside of the space between the lines WX and YZ.

By this invention I provide a method and means by which the errors caused by the 105 tilting of the trunnions of naval guns may readily be compensated for. It has the distinct advantage of extraordinary simplicity. In order to accomplish this result it is necessary to establish a reference plane which 110 always is parallel to the plane of the trajectory and this is easily and accurately done by means of a dead beat pendulum, or any of the other means mentioned above.

Having established such plane, the line of sight may be moved into, or parallel to it, very easily and quickly with the apparatus which I provide, and the source of the greatest error of trunnion tilting is corrected for because the line of sight now lies 115 in a vertical plane parallel to the plane of the trajectory. By utilizing the connection shown in Fig. 3, the line of sight is depressed automatically, by an amount depending upon the angle of tilt of the trunnions, and hence compensate for both errors 120 caused by trunnion tilting.

It might seem, at first thought, that with the second modification of my invention described above, that is, that of indicating 130

the error without correcting it would result in the slowing down of the rate of fire, but this is not the fact. In reality it results in an increase in rate of effective fire, because 5 any gun, or salvo, which would be fired, unless interrupted by my invention, would fall outside the permissible limit of error—possibly many ship lengths outside—and would be thus completely wasted. By pre- 10 venting the fire in this way, another opportunity may come in three or four seconds, instead of only after perhaps half a minute, which would represent the waste time if the salvo from the main battery were 15 thrown away—to say nothing of the enormous expense and waste of the comparative- ly short life of the big guns.

The changes which are required to be made in the apparatus now in use for sight- 20 ing guns in order to embody the principles of my invention are relatively few, and the expense of the installation is consequently low. When the alternative method of in- 25 dicating the maximum permissible limits of error is adopted the expense of the instal- lation is reduced to a minimum and accurate firing of the gun or guns is accom- 30 plished with a minimum of effort on the part of the operators of the gun.

In the above description, my invention is, 35 for the sake of clearness and simplicity shown as applied directly to a gun mount, the necessary corrections of indications be- 40 ing obtained by the movements of the gun and sight. But on the modern battleships this direct application would only be prac- 45 tical on the guns of the secondary battery. The guns of the main battery, to which the application of trunnion tilt correction is of greatest importance, are enclosed in tur- rets and for various reasons the guns are rarely if ever, directed by means of sights mounted directly on a gun, but on the con- trary, are elevated and trained as a result 45 of orders or signals transmitted from a

remote station. It will, however, be obvi- 5ous that my method is quite as applicable to these conditions as it is to direct mounting upon the gun, and that if the direction of train and angular elevation are known, the 50 azimuth error due to trunnion tilt may be easily corrected by means of an apparatus corresponding to the sighting system of the gun, even though such apparatus be located at a remote point in the ship and the cor- 55 rections transmitted electrically or mechani- cally to the gun pointers in the turrets. A single dead beat pendulum can thus be made to simultaneously control the fire of any 60 number of guns.

I claim:—

1. A gun sighting mechanism comprising, a gun mount, a sight yoke universally mounted thereon and means for adjusting said yoke in two planes at right angles to 65 each other, a sight rod mounted on the sight yoke and provided with a reference point, a dead beat pendulum having an indicator in proximity to the reference point, and means for adjusting the sight rod laterally 70 with respect to the sight yoke to keep the reference point opposite the indicator.

2. A gun sighting mechanism comprising, a gun mount, a sight yoke universally mounted thereon and means for adjusting 75 said yoke in two planes at right angles to each other, a sight rod mounted on the sight yoke and provided with a reference point, a dead beat pendulum having an indicator in proximity to the reference point, means 80 for adjusting the sight rod laterally with respect to the sight yoke to keep the reference point opposite the indicator, and means associated therewith for vertically depress- 85 ing the sight rod by an amount proportional to the lateral movement.

In testimony whereof I affix my signature.

SAMUEL LIPPINCOTT GRISWOLD KNOX.
